UNITED STATES PATENT OFFICE

1,945,715

DISCHARGE HEAD FOR FLUID CONTAINERS

Ozro N. Wiswell, Los Angeles, Calif., assignor,
by mesne assignments, to C-O-Two Fire Equipment
Company, Newark, N. J., a corporation
of Delaware

Application January 17, 1931. Serial No. 509,454

8 Claims. (Cl. 169—11)

This invention has to do with a control head or discharge head for releasing fluid from a container, and relates more particularly to a device for actuating a discharge head of a container holding fluid under pressure. The present invention relates to improvements on the general type of device fully described and claimed in

5 Patent No. 1,782,020 of the United States, granted to Scott E. Allen and Ozro N. Wiswell November 18, 1930, entitled Head for puncturing closure.

Containers or cylinders for carrying carbon dioxide, or the like, for use in fire-extinguishing systems, are commonly provided with control heads or discharge heads operable to puncture 15 closures of the containers to release the fluid. Certain types of discharge heads are provided with vertical operating stems adapted to be depressed manually or by mechanical means to cause the release of the fluid from the containers.

20 Containers or cylinders carrying CO₂, or other fire-extinguishing mediums, are sometimes positioned in confined or inconvenient locations where it is difficult to operate the stems of the heads manually, or where it is difficult to provide 25 for the mechanical operation of the stems.

It is a general object of the present invention to provide a control head or discharge head for releasing fluid from a container that embodies an operating means adapted to be set or adjusted 30 for actuation by a force applied in any one of a plurality of different directions.

It is another object of the invention to provide 35 a discharge head of the general character referred to that is adapted to be actuated from a remote point by means of a cable, or the like, and that includes an actuating means that may be set or positioned to allow the cable to extend from the head in any one of a number of different directions.

40 It is another object of the invention to provide an attachment for a discharge head having an operating stem that may be operated from a remote point by means of a cable, or the like, to operate or depress the stem.

45 It is another object of the invention to provide an attachment of the character mentioned that may be actuated by a line or cable and which may be adjusted to have the cable extend from the head in any desired rotative direction and/or 50 in any one of a number of different tangential directions.

55 It is another object of the invention to provide an attachment of the character mentioned that is simple and inexpensive in construction and that is positive and dependable in operation.

A further object of the invention is to provide an attachment of the character mentioned that may be easily and quickly mounted on discharge heads of various types or designs.

Other objects and features of the invention 60 will be best and more fully understood from the following detailed description of a typical form and application of the invention, throughout which description reference will be had to the accompanying drawings, in which:

Fig. 1 is a side elevation of the attachment provided by the present invention illustrating it mounted on a typical discharge head. Fig. 2 is a top or plan view of the device. Fig. 3 is an enlarged vertical detailed sectional view of the 70 discharge head and the attachment. Fig. 4 is a vertical detailed sectional view taken substantially as indicated by line 4—4 on Fig. 3. Fig. 5 is a sectional view taken as indicated by line 5—5 on Fig. 3, and Fig. 6 is an enlarged detailed 75 sectional view taken substantially as indicated by line 6—6 on Fig. 4.

The attachment provided by the present invention is adapted for use in connection with control heads or discharge heads varying somewhat 80 in character. The device is particularly well suited for use on heads of the type having an operating stem adapted to be depressed to cause the discharge of fluid from a container. Throughout the following detailed description the 85 attachment will be described in connection with a discharge head of the general character fully set forth and claimed in the copending application of Scott E. Allen and Ozro N. Wiswell, entitled Non-stalling self-energizing head for puncturing 90 closure discs, Serial Number 349,150, filed March 22, 1930. It is to be understood, however, that the invention is not to be taken as restricted for use on the particular type of head illustrated in the drawings or to the specific details of construction 95 about to be described, but that it is to be taken as including any features or modifications that may fall within the scope of the claims.

The control head or discharge head illustrated in the drawings includes, generally, a body 10, a cutter 11 in the body 10 for opening or puncturing a closure disc 12 of a fluid container, a fluid pressure actuated means 13 for operating the cutter 11, and manual means 14 for operating the cutter.

The body 10 of the head is adapted to be 105 mounted on a container or cylinder holding fluid, for example, carbon dioxide under pressure. It is common practice to provide a fitting or valve member on a fluid containing cylinder to facilitate the filling and discharging of the cylinder. 110

These fittings are commonly termed "cylinder valves", and in Fig. 3 of the drawings I have illustrated a typical cylinder valve 15 which may be considered as being mounted on the upper end of a fluid containing cylinder. The fitting or cylinder valve 15 is provided with a central vertical opening or passage 16 adapted to communicate with the interior of the container. The upper portion of the valve 15 may be of enlarged diameter and may be externally screw threaded as illustrated in the drawings. The upper portion of the passage 16 is of enlarged diameter, and a tubular nut 17 is threaded therein to retain the closure disc 12 in position where it closes the upper end of the passage 16. The closure disc 12 is frangible and is adapted to be cut or perforated by the cutter 11, as will be hereinafter described.

The head body 10 is detachably mounted on the upper end of the cylinder valve 15. The body 10 may be detachably mounted on the cylinder valve 15 by means of a union or coupling member 18 screw threaded onto the enlarged upper end of the cylinder valve. A cylindrical chamber or cylinder opening 19 is provided in the body 10. The cylinder opening 19 extends upwardly in the body 10 from its lower end, and its upper end portion is of reduced diameter.

The cutter 11 is provided to cut out or puncture the frangible disc 12 and is carried within the cylinder opening 19 by the fluid pressure actuated means 13. In the particular type of discharge head illustrated in the drawings, the cutter 11 is tubular, having a central longitudinal opening 20. The lower end of the cutter 11 is inclined and provided with sharpened edges to effectively cut the frangible closure disc 12.

The fluid pressure actuated means 13 for operating the cutter 11 is in the nature of a cylinder and piston means and includes a piston 21 operable in the cylinder opening 19. A head 22 may be provided on the upper end of the cutter 11 and may be screw threaded into the lower end of a fluid passage 23 in the piston 21. The upper end of the piston 21 may be of reduced diameter, and the passage 23 may extend upwardly into the reduced end of the piston. The opening 20 of the cutter communicates with the passage 23 to discharge fluid into the passage, and lateral ports 24 are provided in the piston to extend from the passage 23 to the upper portion of the cylinder opening 19. Conduits 25 communicate with the upper end portion of the cylinder opening 19. In the case illustrated there are two conduits 25 one of which may be considered as being connected with the cylinder opening of a discharge head, while the other may be taken as discharging into a discharge line or manifold.

A check valve may be provided in the passage 23 to prevent the flow of fluid under pressure downwardly through the opening 20. A ball 26 may be arranged in the passage 23 to cooperate with a seat in the upper end of the opening 20 to prevent fluid from passing downwardly through the cutter. Lateral ports or vents 27 may be provided in the lower portion of the body 10 to permit the escape of air or fluid trapped in the lower portion of the cylinder opening upon actuation of the head. A sealing washer 28 may be mounted on the lower end of the piston 21 to seal with the upper end of the nut 17 when the piston is in the down or actuated position. It will be apparent how fluid discharged into the upper end of the cylinder opening 19 from a conduit 25 actuates

the piston downwardly to cause the cutter 11 to puncture the closure disc 12.

The means 14 for manually operating the discharge head includes a stem 29 projecting upwardly from the reduced upper end of the piston 21. The stem 29 slidably passes through an opening 30 in the body 10 to project above the upper end of the body. A knob or head 31 may be provided on the upper end of the operating stem 29. A helical spring 32 is arranged under compression between the body 10 and the head 31 to normally yieldingly hold the piston 21 and cutter 11 in the up or unactuated position.

The attachment provided by this invention is intended primarily to operate or depress the stem 29 to actuate the head 10 and is such that it may be controlled or operated from a remote point either manually or mechanically. The attachment includes, generally, a casing or body 33 adapted to be mounted on the upper end of the body 10 of the head, a cam 34 in the body 33 for operating the stem 29, a sheave or drum 35 in connection with the cam 34 for carrying a cable C for rotating the cam, and a head or end plate 36 for the casing 33.

The casing or body 33 of the attachment is adapted to be detachably mounted on the upper end of the head body 10 and is provided to carry the various parts of the attachment. The body 33 may be round or cylindrical in its general configuration and may be provided at its lower end with a polygonal boss 37. The boss 37 is provided with a screw threaded opening 38 for connecting with or receiving a screw-threaded pin 39 on the upper end of the head body 10. In accordance with the invention, the casing or body 33 may be set in any rotative position desired by turning or threading the boss 37 on the pin 39. The body 33 may be set in the desired rotative position by means of a set screw 40 carried by the boss 37 for clamping against the threaded pin 39.

The casing 33 is chambered or provided with an opening 41 for containing the cam 34. The opening 41 is preferably round in cross section and has a horizontal central longitudinal axis. The longitudinal axis of the opening 41 is preferably normal to the longitudinal axis of the operating stem 29. The chamber or opening 41 joins or communicates with the upper end of the opening 38. The opening 38 passes the operating stem 29, and the upper end of the stem and the head 31 are normally disposed within the opening 41. The opening 41 extends to or is open at what we will term the outer side of the casing, and a radially projecting flange 42 is provided on the casing 33 around the outer end of the opening 41.

The cam 34 is rotatably or pivotally mounted within the casing body 33 and is in engagement with the upper end of the head 31. The cam 34 is pivotally supported by the end plate or head 36, as will be hereinafter described. The axis of pivotal movement of the cam 34 is preferably concentric with the central horizontal axis of the opening 41. The exterior of the cam 34 presents a curved cam face 43 for cooperating with the head 31 to depress the stem upon operation of the cable C. The cam face 43 may be in the nature of a continuously curved face and preferably extends a considerable distance around the cam. The cam face 43 terminates at its innermost end at a flat face or shoulder 44. The cam 34 is normally in a rotative position where the flat shoulder 44 is in engagement with the upper end of the head 31.

The cam face 43 may extend around the cam 34 from one end of the shoulder 44 to the other

and may be such that it cooperates with the head 31 to depress the stem 29 upon the cam being rotated in a clockwise direction. The invention provides stop means for limiting the pivotal movement of the cam 34. A pin 45 projects from the inner end of the cam 34 and is adapted to cooperate with a stop projection 46 on the inner wall of the opening 41. The pin 45 may be positioned to engage the stop projection 46 when the cam 34 is in the unactuated position to prevent rotation of the cam in a counterclockwise direction.

The sheave or drum 35 is provided to carry the active end portion of the line or cable C. In practice the drum 35 may be formed integral with the cam 34 and may be in the nature of an axial flange of enlarged diameter projecting from the outer end of the cam. The cable carrying exterior of the drum 35 is cylindrical and concentric to the axis of rotation of the cam 34. The bulk or major portion of the drum 35 projects beyond the outer end of the casing body 33 and is enclosed by the head 36. A radial flange 47 may be provided at the outer edge of the drum 35 to 25 prevent displacement of the cable C from the drum.

The operating line or cable C may be formed of suitable cord, wire, cable, or the like. The line C is provided to cause turning of the cam 34 to actuate the head and may be considered as extending to a remote point where it may be operated or pulled manually or by suitable mechanical means. The end of the line C is attached to the drum or cam, and the line has several turns or windings on the drum. It is preferred to have at least two turns or windings of the cable C on the drum 35 when the parts are in the normal or unactuated position. In accordance with the broader principles of the invention, the cable C may be attached to the drum or cam in any suitable manner. In the particular case illustrated, the end portion of the line or cable passes inwardly through a groove or opening 48 to the inner end of the cam 34. The line 45 may be wrapped about a screw 49 threaded into an opening in the inner end of the cam and countersunk in the end of the opening 48. The screw 49 effectively connects the cable C with the cam. The extreme end part of the cable C 50 may pass from under the head of the screw 49 into a groove 50 in the cam.

The head or end plate 36 closes the open end of the casing body 33 and rotatably supports the cam 34. The head 36 is round or cylindrical in its general configuration, and its inner side is relieved or provided with an annular recess 51 to carry the drum flange 35. A radially projecting annular flange 52 is provided at the inner end of the head 36 to seat against the flange 42. The flanges 42 and 52 are preferably of the same diameter. The head 36 is attached to the casing body 33 by a plurality of screws 53 arranged through equally spaced openings in the flange 42. There may be any desired number of screws 53 and they may pass through openings in the flange 42 and thread into openings 70 in the flange 52. In the preferred form of the invention there are a comparatively large number of threaded openings 70 in the flange 52 so that the head may be set in various rotative positions. The screws 53 are readily removed to permit the setting of the head 36 in any desired rotative position.

The means for rotatably or pivotally supporting the cam 34 includes a stub shaft or trunnion

54 projecting from the outer end of the cam. A boss 55 is provided on the inner side of the head 36, and its inner end may engage the outer end of the cam. The trunnion 54 is rotatable in a central opening 56 in the boss 55 and head. 80 The trunnion 54 may extend completely through the opening 56, and a pin 57 of reduced diameter may be provided on the outer end of the trunnion to project from the head 36. A central bearing projection 58 may be provided on the inner wall of the opening 41 to engage the inner end of the cam 34. The cam is held against axial movement between the bearing projection 58 and the inner end of the boss 55. A pointer arm 60 may be mounted on the pin 57 to indicate the rotative position of the cam 34. The reduced pin 57 may be provided with a flattened side, and an opening 61 of corresponding configuration is provided in the arm 60 to receive the pin. A screw 62 may be provided to secure the arm 60 to the trunnion 54. The arm 60 may be set so that it is vertical when the cam 34 is in the unactuated or normal position, and an arrow or marking 63 may be provided on the inner side of the flange 42 to indicate the proper normal 95 position of the arm 60. The arm 60 preferably projects beyond the flanges 42 and 52 so that it is visible from either end of the attachment. 100

An opening 64 is provided in the head 36 to pass the cable C from the casing. The opening 64 105 is preferably tangential to the drum 35 and is sufficiently large in diameter to pass the line or cable with considerable clearance. A guide boss 65 may be provided around the outer end of the opening 64 to guide the cable. 110

The casing body 33 of the attachment may be mounted on the control head in any desired rotative position by turning the boss 37 to the desired position on the pin 39. The set screw 40 may be employed to set the casing in the desired position. The head or end plate 36 may be removed from the casing by unthreading or removing the screws 53 from the openings 70. The head may then be turned so that the line or cable C will extend from the attachment in the desired direction. The screws 53 may then be threaded into the openings 70 in the flange 52 to clamp the head in the desired position. It is to be understood that during removal and adjustment of the head 36 that the cam 34 or arm 60 need not be 120 disturbed as the head may be readily turned or rotated on the trunnion 54. There may be any desired number of spaced openings 70 provided in the flange 52 to receive the ends of the screws 53 so that the head 36 may be set in any number 130 of different rotative positions. To actuate the discharge head the line or cable C is pulled to cause turning or pivoting of the cam 34. Upon turning of the cam 34, the cam face 43 cooperates with the upper end of the head 31 to depress the 135 stem 29 and operate the cutter 11 through the frangible closure disc 12. The fluid released through the cutter 11 and piston opening 23 may discharge through either one or both of the conduits 25. 140

It is to be noted that the present invention provides an actuating attachment for a control head that may be set or adjusted so that an actuating cable may extend from the head in any direction. The attachment is readily set or adjusted 145 for actuation by forces applied to the cable C in different directions. The device is simple in construction and is positive and effective in operation.

Having described only a typical preferred form 150

of my invention, I do not wish to limit myself to the specific details set forth, but wish to reserve to myself any changes or variations that may appear to those skilled in the art or fall within the scope of the following claims:

Having described my invention, I claim:

1. A device for use on a discharge head for a container having a movable operating member for opening the container, said device including a body to be applied to the head, a cam carried by the body for operating the said member, a flexible element for actuating the cam, and means whereby the element may be made to pass from the body in any one of a plurality of different directions, said means including a cover member for the body having an opening for passing the element from the body, and means for removably attaching the cover member to the body in different positions.
2. A device for use on a discharge head for a container having a movable operating member for opening the container, said device including a body to be applied to the head, a cam carried by the body for operating the said member, a flexible element for actuating the cam, and means whereby the element may be made to pass from the body in any one of a plurality of different directions, said means including a cover member for the body having an opening for passing the element from the body, and screws for removably attaching the cover member to the body in any one of a plurality of rotative positions.
3. A device for use on a fluid container discharge head having a movable operating member, which includes a body to be applied to the head, a cam carried by the body for operating the said member, a drum in connection with the cam, a flexible element wound on the drum for operating the cam, a head on the body having an opening for passing the element from the body, and means for attaching the head to the body in any one of a plurality of different rotative positions.
4. A device for use on a discharge head for a container having a movable operating member for opening the container, said device including a body to be applied to the head, a cam carried by the body for operating the said member, a drum in connection with the cam, a flexible element wound on the drum for operating the cam, a head on the body having an opening for passing the element from the body, and means for attaching the head to the body in any one of a plurality of different rotative positions so that the element may pass from the drum in different

55

60

65

70

directions, said means including a screw passing through an opening in the head and adapted to be threaded into any one of a plurality of spaced openings in the body.

5. A device for use on a fluid container discharge head having a movable operating stem which includes, a body adapted to be mounted on the head, a cam within the body for operating the stem, a drum in connection with the cam, a flexible operating element wound on the drum, a head for the body having an opening for passing the element from the body, means whereby the head may be attached to the body in different rotative positions so that the element may pass from the body in different directions, and means on the head for pivotally supporting the cam.

6. A device for use on a fluid container discharge head having a movable operating stem which includes, a body adapted to be mounted on the head, a cam within the body for operating the stem, a drum in connection with the cam, a flexible operating element wound on the drum, a head for the body having an opening for passing the element from the cable, means on the head for pivotally supporting the cam in the body, and means for detachably mounting the head on the body in any one of a plurality of different rotative positions.

7. A device for use on a fluid container discharge head having a movable operating stem which includes, a body adapted to be mounted on the head, a cam within the body for operating the stem, an end plate on the body pivotally supporting the cam, a drum on the cam within the end plate, a flexible element wound on the drum for operating the cam, there being an opening in the end plate for passing the cable from the body, and means for detachably mounting the end plate on the body in any one of a plurality of different rotative positions so that the element may pass from the body in different directions.

8. A device for use on a fluid container discharge head having a movable operating stem which includes, a body adapted to be mounted on the head, a cam within the body for operating the stem, a drum in connection with the cam, a flexible operating element wound on the drum, a head for the body having an opening for passing the flexible element from the body, a shaft on the cam passing through an opening in the head, and an indicating arm on the shaft at the exterior of the body.

OZRO N. WISWELL.
